REVOLVING SPUD LINE

Benjamin F. Bowman, Clarksburg, W. Va.

Application August 29, 1951, Serial No. 244,124

8 Claims. (Cl. 255—11)

1

This invention relates to a revolving spud line for use in a cable tool drill. In the cable tool branch of the drilling industry, deep well spudders are rapidly reaching a dominant position, having almost completely supplanted the old fashioned derrick and beam equipment. Their popularity is due to quick, easy transportation and erection, rather than greater efficiency. In fact it is doubtful that they will ever attain quite the respect accorded the standard rig by many drillers. However, many of the present bottlenecks will be eliminated in time and an effort toward this end is the objective of the revolving spud line described herein.

A further object of the revolving spud line of this invention is conservation of drilling cable which is relieved of constant wear on the crown pulley which many times has burned out the hemp core, causing the cable to collapse.

Still a further object of this invention is to provide a revolving spud line, sometimes known as a jerk line, wherein the spud or jerk line is made in the form of a very fine strand, very flexible wire cable endlessly looped about a rotatable sheave on the spudder and passing over a pulley system on the mast to a spud supporting sheave and pulley block together with means for causing said endless looped cable to be revolved at least a slight amount for each reciprocation of the spudder and the spud to thus distribute the wear throughout the spud line and greatly lengthen the life thereof instead of having the wear concentrated at any particular point or points therealong.

With the foregoing and other objects in view, this invention comprises the combination, construction and arrangement of parts hereinafter set forth, claimed and disclosed in the accompanying drawings, wherein:

Fig. 1 is an elevational view of the spudding mechanism of a cable tool drill to which this invention has been applied.

Fig. 2 is a front view of the mast and supporting means of Fig. 1.

Fig. 3 is a fragmentary view on line 3—3 of Fig. 1.

Fig. 4 is a top plan view of Fig. 3, and

Fig. 5 is a sectional view on line 5—5 of Fig. 3.

There is shown at 10 the spudding mechanism of a cable tool drill and includes a pair of spaced apart tubular telescoping masts supported on a base 12 which may be portably mounted on a truck or other vehicle. The mast 11 may be maintained in spaced apart relationship by connecting plates 13 and 14.

Pivotedly supported on a stationary bearing 15

is the spudder 16 so that its free end 17 may reciprocate up and down as shown by the double ended arrow 18 by any conventional crank and pitman power assembly (not shown).

5 The spudder 16 includes a sheave 20 rotatably mounted thereon by means of a removable pivot 21 extending across a sheave receiving slot 22 in a cross beam 23 pivotedly secured at 24 at both ends between the spaced apart arms 25 at the end 17 of the spudder 16.

10 Looped about the sheave 20 is the revolving spud line 26 of this invention. From the sheave 20, the line 26 passes up over a pair of spaced apart pulleys 27 which as shown may be suspended 15 at 28 from the cross plate 14 of the tubular mast 11 and then passes downwardly over a pair of spaced apart aligning pulleys 30 rotatably supported on brackets 31 from the lower cross plate 13, and then about the sheave 32 of an inverted pulley block 33 from which the spud is supported 20 in the hole by means of the usual conventional temper screw and clamp assembly (not shown).

15 The pulleys 27 serve to support the spud line 26 thereover while the sheaves 30 serve to align the spud supporting pulley block 33 over the center line of the drilled hole. As will be apparent, reciprocation of the spudder 16 about its bearing support 15 as shown by the doubled arrow 18 will correspondingly raise and lower the sheave supporting block 33 to thereby raise and lower the spud in the usual manner. All the pulleys or 20 sheaves will preferably be equipped with anti-friction roller or ball bearings and are constructed with the single block open feature to permit the threading of the endless spud line 26, and such construction being conventional, need not be here described in detail.

25 The sheave 20 on the spudder 16 is provided with a fairly wide groove for the spud line 26 so that at the bottom of its reciprocation, a friction wheel 34 may enter into the recess and contact the spud line 26 thereon. This friction wheel 34 is provided with a friction periphery 35 having a contact surface of fiber or solid or pneumatic rubber or any suitable grip providing surface.

30 The friction wheel 34 is mounted on a shaft 36 extending from a small electric motor 37 at one end and into a suitable bearing support 38 at the other end. The motor 37 and the bearing support 38 are each adjustably mounted by an adjusting screw means 40 on a base 41 supported on yieldable coil springs 42 on a suitable foundation 43 on the base 12. In operation, during drilling, the motor 37 will be kept constantly rotating, and as the spudder 16 reciprocates up and 35 down, the spud line or jerk line 26 passing about

2

the sheave 29 will be brought into momentary or intermittent contact with the peripheral friction surface 35 of the friction wheel 34 and thus cause to revolve slightly about the various sheaves or pulleys on which it is supported as well as about the sheave 32 which supports the spud. This distributes the wear throughout the line 26 instead of permitting the wear to concentrate as with the present system where it passes over the crown block as well as other points under tension. As a result of the provision of the coiled supporting springs 42, the friction wheel 34 is yieldably mounted and the contact between the friction wheel and the spud line is not too rigid. By making the bases 41 adjustable by means of the adjusting screw 48 or other adjusting means, it is possible to conform with the desired drilling stroke, as well as to apply a little firmer contact as the depth of the well and the tension progressively increase. As the contact between the friction wheel periphery 35 contacting the line 26 is made at the very crest of the drilling stroke where tension is at a minimum, the line 26 should revolve easily. Obviously instead of the friction wheel periphery 35 contacting the line 26 to apply the revolution thereto, it could instead contact the sheave 29 to rotate the sheave and thus indirectly provide rotation to the line 26.

The essential feature of this invention is that instead of providing a single spud or jerk line between the spudder and the spud, this invention provides an endless looped revolving spud line and a means for intermittently revolving the line with each reciprocation of the spudder to thus distribute the wear throughout the line and greatly lengthen the life thereof. The line 26 may preferably be made of a very fine strand of very flexible wire cable of $\frac{3}{4}$ to $\frac{7}{8}$ inch diameter and of a circumferential length of approximately 80 feet more or less for use in a cable tool drill which is otherwise of conventional construction.

While the device has been shown and the structure described in detail, it is obvious that this invention is not to be considered as being limited to the exact form disclosed, and that changes in detail and construction may be made therein within the scope of what is claimed, without departing from the spirit of this invention.

Having thus set forth and disclosed the nature of this invention, what is claimed is:

1. In the spudding mechanism of a cable tool drill, a revolving endless looped spud line connecting the reciprocating spudder to the reciprocating spud, the reciprocating spudder and the reciprocating spud each having a rotatable sheave about which said spud line is looped, and a rotating member making contact with said endless looped spud line to thereby revolve said spud line and distribute the wear thereover.

2. In the spudding mechanism of a cable tool drill, a revolving endless looped spud line connecting the reciprocating spudder to the reciprocating spud, the reciprocating spudder and the reciprocating spud each having a rotatable sheave about which said spud line is looped, and a continuously rotating member in the path of reciprocation of said endless looped spud line making momentary connection to said spud line at each reciprocation thereof to thereby slightly revolve said spud line at each reciprocation and thus distribute the wear thereover.

3. In the spudding mechanism of a cable tool drill, a revolving endless looped spud line connecting the reciprocating spudder to the reciprocating spud, the reciprocating spudder and the

reciprocating spud each having a rotatable sheave about which said spud line is looped, and means for revolving said spud line intermittently at each reciprocation of the spudder comprising a rotating friction wheel supported in the path of the rotatable sheave on said spudder and adapted to be contacted at each reciprocation of said spudder supported sheave to thereby impart intermittent revolution to said looped spud line to distribute the wear thereover.

4. In the spudding mechanism of a cable tool drill, a revolving endless looped spud line connecting the reciprocating spudder to the reciprocating spud, the reciprocating spudder and the reciprocating spud each having a rotatable sheave about which said spud line is looped, and means for revolving said spud line intermittently at each reciprocation of the spudder comprising a rotating friction wheel yieldably supported in the path of the rotatable sheave on said spudder and adapted to be contacted at each reciprocation of said spudder supported sheave to thereby impart intermittent revolution to said looped spud line to distribute the wear thereover.

5. In the spudding mechanism of a cable tool drill, a spud line comprising a flexible endless looped cable, an inverted spud supporting sheave and pulley block through which said cable is looped, a mast supported pulley system over which said cable is revolvably supported, a reciprocable spudder and a sheave rotatably supported thereon over which said cable is looped, whereby reciprocation of said spudder reciprocates said looped cable to thereby reciprocate said spud supporting sheave and pulley block, and means for revolving said looped cable about its sheaves to thus distribute the wear thereon.

6. In the spudding mechanism of a cable tool drill, a spud line comprising a flexible endless looped cable, an inverted spud supporting sheave and pulley block through which said cable is looped, a mast supported pulley system over which said cable is revolvably supported, a reciprocable spudder and a sheave rotatably supported thereon over which said cable is looped, whereby reciprocation of said spudder reciprocates said looped cable to thereby reciprocate said spud supporting sheave and pulley block, and means for revolving said looped cable about its sheaves at each reciprocation of said spudder comprising a rotating friction wheel supported in the path of said spudder supported sheave and cable loop thereon whereby said friction wheel will be contacted at each reciprocation of said spudder to thereby revolve said cable about its sheaves a slight amount and thus distribute the wear thereon.

7. In the spudding mechanism of a cable tool drill, a spud line comprising a fine strand flexible endless loop wire cable, an inverted spud supporting sheave and pulley block through which said cable is looped, a mast supported pulley system over which said cable is revolvably supported, a reciprocable spudder and a sheave rotatably supported thereon over which said cable is looped, whereby reciprocation of said spudder reciprocates said looped cable to thereby reciprocate said spud supporting sheave and pulley block, and means for revolving said looped cable about its sheaves at each reciprocation of said spudder comprising a constantly rotating friction wheel yieldably supported in the path of said spudder supported sheave and cable loop thereon whereby said friction wheel will be contacted at each reciprocation of said spudder to thereby

revolve said cable about its sheaves a slight amount and thus distribute the wear thereon.

8. In the spudding mechanism of a cable tool drill, a spud line comprising a fine strand flexible endless looped wire cable, an inverted spud supporting sheave and pulley block through which said cable is looped, a mast supported pulley system over which said cable is revolvably supported, and a reciprocable spudder and a sheave rotatably supported thereon over which said cable is 10 looped, whereby reciprocation of said spudder reciprocates said looped cable to thereby reciprocate said spud supporting sheave and pulley block, and means for revolving said looped cable about its sheaves at each reciprocation of said 15

spudder comprising a constantly rotating friction wheel adjustably and yieldably supported in the path of said spudder supported sheave and cable loop thereon whereby said friction wheel 5 will be contacted at each reciprocation of said spudder to thereby revolve said cable about its sheaves a slight amount and thus distribute the wear thereon.
